MACHINE TO RIVET TWENTY SHORT SPOKES WITH HUB AND RIM TOGETHER

Herman Tormyn and Frank F. Wiethoff, Detroit, Mich., assignors to General Motors Corporation, Detroit, Mich., a corporation of Delaware

Application July 29, 1932, Serial No. 625,998

12 Claims. (Cl. 78—16)

This invention relates to the manufacture of wire wheels and has particular reference to a machine or die to rivet twenty short spokes between the wheel hub and rim. The machine of the invention is one of a series of ten and in sequence of operation follows the machine or die of our copending applications, Serial Nos. 625,995, 625,996 and 625,997, filed July 29, 1932.

The die of the invention is applied to a conventional press and comprises a lower die shoe and a top shoe. The assembled hub, short spokes and rim are positioned in the die shoe with a fixture to form a backing for the spoke heads inside the hub. Suitable punches and the means to operate them are mounted in the die shoe and are operated by the movement of the top shoe on the die shoe. The spokes are suitably held by cooperating anvils on the two shoes adjacent the rim and a rubber pad is provided on the top shoe so that the anvils will be properly equalized and exert a substantially similar pressure on all of the spokes. A suitable plunger mounted in the top shoe strikes against and presses on the fixture when the top shoe is moved toward the die shoe.

On the drawings:

Figure 1 is a front view of a press with the invention applied.

Figure 2 is a side view of the structure of Figure 1.

Figure 3 is an enlarged sectional detailed view through the die of the invention taken on the line 3—3 of Figure 5 showing the shoe descended on the lower shoe and with the punches heading the spoke ends at the rim.

Figure 4 is a view corresponding to Figure 3 but showing the top shoe in raised position and with assembled wheel and headed spokes raised from the die shoe.

Figure 5 is a plan view substantially on the line 5—5 of Figure 4.

Figure 6 is a perspective view of one of the anvils on the die shoe.

Figures 7 and 8 are perspective views of two of the elements of the fixture for backing the spokes inside the wheel hub.

Figure 9 is a perspective view of one of the anvils of the top die.

Referring to the drawings, the numeral 2 indicates the upright frame of the press. On the frame there is mounted the source of power 4 such as an electric motor having the pulley 6 to drive the belt 8. The belt 8 in turn drives the flywheel 10 and the shaft 12. The shaft 12 extends through the machine and the other side has

a pinion (not shown) secured thereto which drives a large gear wheel 14 rigidly mounted on the shaft 16 having a crank 18 intermediate its ends and working in the frame 2. The crank 18 has the connecting rod 20 mounted thereon which is suitably connected to a crosshead 24 which is in turn connected to the top shoe 26 of the die 28. The lower shoe of the die is indicated at 30 and has the hydro-pneumatic cylinder 32 having a suitable piston (not shown) connected by a piston rod 34 to a plate 36. The plate 36 is in turn connected by means of the rods 38 to the plate 40 on which there rest the pressure pins 42. The cylinder 32 is of the hydro-pneumatic type and is provided with a suitable pipe system to allow ingress and egress of the air and liquid in timed relation with the action of the press. The plates 36 and 40 are slidable in the base of the press 30.

The crosshead 24 also has a hydro-pneumatic cushion which includes an air pipe 44 leading to an air chamber 46 having the piston 48 therein and an oil line 50 leading to a chamber 52. A partition 54 separates the chambers 46 and 52 and suitable passages (not shown) are provided in the partition to allow the oil to flow from one chamber to the other. The piston 48 has a stem 56 the end of which is bored and which extends through a partition indicated at 60. There is a spring loaded check valve at the end of the bore at 62. The head end 62 is adapted to contact with the piston 64 at the lower part of the chamber 52. A suitable coil spring 66 between the head 62 and the partition 60 constantly urges the piston 48 and stem 56 downwardly. The parts described are mounted in a cylinder 68 formed on the crosshead 24. Excessive pressure below the partition 60 will crack the check valve to allow oil to flow to the chamber 52.

An operating handle 70 adjacent the front of the machine operates a linkage 72 to operate a clutch to throw the wheel 14 into operation. The clutch is so arranged that after one rotation of the crank 18 the machine will stop and the clutch must again be thrown into operation by the movement of the handle 70. A stop brake is shown at 74 with the brake shoes 76 and the operating linkage 78.

The parts so far described and their operation are conventional and per se form no part of the invention.

Referring to Figures 3 and 4 the bottom or die shoe 30 comprises the lower flat portion 80 which has rigidly mounted at the periphery thereof the upper and lower bearing forming rings 82 and 84 secured to the base 80 by means of the ma-

chine bolts 86. The flat bottom member 80 has the inner periphery of the lower bearing forming member 84 forming a cylindrical surface indicated at 88 in which there is slidably mounted the 5 pad 90 constantly urged upwardly by the pressure pins 42 receiving the upward pressure of the piston in the cylinder 32.

The upper peripheral portion of the head 90 is provided with ten grooves 92 in which there are 10 received the ten punch slides 94 having the punches 96 mounted at the inner ends thereof and held in the punch slides by means of set screws 98 as shown in Figures 3 and 4. A top retaining ring 100, having a plurality of tines 102 15 projecting downwardly between the punch holders 94, forms a bearing and retaining means for the punch slides 94. The retaining ring 100 is secured to the pad 90 by means of the machine bolts 104. A suitable tongue and groove connection 106 positions the ring 100 with reference to the pad 90.

Each punch holder 94 has a recessed portion 108 at its rear and between the forks formed by the recess there is pivoted the arm or link 110 by 20 means of the pivot pin 112. The outer end of the arm is formed into a rounded head 114 which is received in the bearing portions 116 and 118 formed at the inner edges of the bearing forming 25 rings 82 and 84. The inner ends 115 of the links 110 are machined to bear against a corresponding machined portion on the slides 94 so that there will be no pressure on the pins 112 when the links 110 push the slides inwardly. The slides 94 are slidably mounted in the spaces formed by 30 the pad 90 and the top ring 100 with its tines 102.

Secured concentrically on the pad 90 is the rim receiving ring 120, the exterior portion of which is shaped as shown at 122 to receive the similarly shaped portion of rim 124. The ring 40 120 is secured to the pad 90 by means of machine bolts 126.

Secured to the top of the ring 120 around its outer periphery adjacent the rim 124 there are the ten anvils 128 one of which is shown in perspective in Figure 9. The anvils are secured in place by means of suitable machine bolts fastened through openings 130 at the ends of the anvils. Each anvil has the steps 132 and 134, the former of which is somewhat elevated relative to the latter. Each step has the groove or recessed portion 136 which is shaped snugly to receive one 50 spoke of the wheel.

The central portion of the pad 90 as well as the flat portion 80 and the die shoe are hollow as 55 indicated at 138, and mounted in the pad immediately surrounding the hollow portion 138 is the positioning ring 140 to receive the hub shell 142. The upper inner periphery of the ring 140 is shaped as shown at 144 to receive the outer edge 60 of the hub shell 142. The upper portion of the ring 140 is provided with a plurality of recesses 146 the purpose of which is to receive the spokes 148, each recess accommodating two spokes.

Prior to positioning the hub shell 142 in the 65 opening 138 and on the shoulder 144 of the ring 140 a fixture 150 is secured thereto and mounted in the larger end of the shell. The fixture 150 comprises the circular backing ring 152 having the edge flange 154 which is tapered or conical 70 and which backs or supports the heads of the spokes 148 rigidly to hold them in their openings in the hub shell and firmly to press them outwardly so that the ends of the spokes will project through the openings in the rim 124. 75 This backing ring 152 is shown in perspective in

Figure 8. A head 160 shown in perspective in Figure 7 has a flange 162 which fits over the edge of a central opening in the backing member 152. The head 160 extends through the opening in the bolt flange 164 and has pivoted in slots 166 around its periphery the levers 168, the inner ends 170 of which are received in the groove 172 in the head 174 of a bolt 176 threaded at 178 and received in the threaded portion 180 of the center of the head 160. The outer ends 10 182 of the levers 168 are adapted to strike against the inturned flange 183 on the inner periphery of the bolt flange 164. When the bolt 176 is screwed downward (when considering the structure of Figures 3 and 4) the engagement of the groove 15 172 with the end 170 will force the levers to the position shown in Figure 3. A cap 185 is secured to and covers the lower end of the head 160.

By the application of a wrench to the squared 20 head 184, the bolt 176 may be turned upwardly to swing the levers 168 on their pivots 186 and to throw the ends 182 inwardly of the head 160 so that the fixture 150 may be withdrawn from 25 the hub shell. The backing ring 152 and the head 160 may be secured together in any suitable way.

The upper or top die 26 is suitably secured to the crosshead 24. The central portion of the top die 26 is hollow as indicated at 188 for the 30 reception of the shank portion 190 of a plunger 192. The plunger 192 is secured to the piston 64 by means of the machine bolt 193 and a suitable retaining ring 196 is secured by means of 35 machine bolts 198 to the cylinder 68 and limits the downward movement of the piston 64 relative to the top shoe. The plunger 192 has the flanged head 194 which is adapted to strike against the upper flat surface of the backing member 152 when the top die descends on the 40 lower die. The pneumatic part of the upper hydro-pneumatic cushion acts on the piston 64 insofar as the fixture 150 is concerned.

Inner and outer retaining rings 200 and 202 45 secured to the top die 26 by means of machine bolts 204 hold an anvil retaining ring 206 in place. Each retaining ring 200 is provided with suitable shoulders which cooperate with corresponding shoulders on the retaining ring 206 50 the structure being indicated at 208. An annular rubber pad 210 is positioned between the anvil ring 206 and the top die 26.

The lower face of the anvil ring 206 has secured thereto the ten top anvils 212 which are 55 similar to the anvil 128. The anvils 212 and 128 mate or cooperate with each other and permanently and rigidly hold the spoke ends therebetween during the action of the punches 96, as shown in Figure 3.

The position of the anvils when they retain 60 the spokes is shown in Figure 3. The anvils 128 and 212 never contact at their surfaces 213 but when the spokes are held therebetween they very tightly and firmly grip the spoke ends which keep the surfaces 213 slightly spaced. In this figure the rubber pad 210 acts to equalize the pressure of the upper anvil so that all of the spokes are held under substantially the same pressure.

Referring to Figure 4 it will be seen that with 65 drawing hooks 214 are provided. Preferably two of these hooks are used one at each side of the machine 180° apart. The hooks 214 have the T-heads 216 secured to the outer retaining ring 202 by the machine bolts 218. A lever 222 in a 70 75

passage 224 in the lower end of the hooks 214 has toothed end 226 which is adapted to engage under the top of the flange of the rim 124. The lower edge of the hook end 226 is beveled as shown in Figure 4, the purpose of which is to allow it to ride over the edge flange when the top shoe 26 is descending. The passage 224 is sufficiently large to allow the hook 226 to turn thereinto and to pass over the edge flange. 5

10 When the lever 222 and its end 226 have passed over the edge flange of rim 124 a coil spring 228 enclosed in the passage 230 in the hooks 214 pulls the lever 222 to the position shown in Figure 4 so that when the top shoe 26 is raised the hooks 15 10 will pull the assembled hub shell, rim and spokes away from its position on the die shoe 30. When the top shoe has been raised the operator may seize rim 124 and pull the assembly from the machine so that the fixture 150 may be 20 removed and a new assembly inserted in the machine. The ring 100 and pad 90 have suitable passages 231 (Figure 5) to allow the hooks to move into the die shoe.

25 The operation of the device is as follows: the position of the parts before the top shoe descends on the lower shoe is shown in Figure 4. The hub shell 142, rim 124 and spokes 148 have been hand assembled and with the fixture 150 will be positioned on the lower or die shoe 30 instead of suspended as shown in the figure. The 30 operator now moves the handle 70 to cause the crank 18 to make one revolution. This will force (1) the top die 26 to descend on the die shoe 30 and bring the plunger 192 in contact with the 35 backing member 152; (2) the upper anvils 212 will strike the spokes and rigidly grip them at the rim, the rubber pad 210 being compressed; (3) the outer retaining ring 202 to contact with the lower retaining ring 100; (4) and the spacer 40 232 surrounding the guide bolt 234 in contact with the upper bearing forming ring 82. All of these parts do not contact at the same time, the plunger 192 first striking the backing member 152, the anvils 212 then contacting the spokes, the ring 202 then striking the retaining ring 100, and when the crank 18 reaches the bottom-most position of its movement the spacers 232 will strike the ring 82. The movements which 45 take place due to the contact of the various parts mentioned is as follows: The pad 90 will be pushed downward, first against the resistance of the pneumatic part of the hydro-pneumatic cushion, and then against the entire resistance of the cushion, which will cause links 110 to be swung on the pivots formed by the heads 114 and surface 116, 118, to force the punch holders 94 inwardly to cause the punches 96 to head the ends of the spokes 148 at the rim. The anvils 128 and 212 will rigidly grip the spoke ends adjacent the rim while the punches are acting. These operations are in timed relation and will permanently head the spokes and when the heading operation is complete the top die will raise to the position shown in Figure 4, allowing the pressure pins 42 to push the pad 90 upward to withdraw the punches. The hooks 214 will carry the wheel up with them.

We claim:

1. In a machine for riveting the short spokes of a wire wheel between the hub shell and rim, a die shoe a reciprocable pad mounted therein, means on the pad to position the assembled hub shell, rim and spokes, a fixture secured in the hub shell and abutting the headed ends of the 70 spokes rigidly to hold them in their openings in the shell, a plurality of anvils on the die shoe adjacent the rim to receive and positively position the spoke ends, a top die movable to and from the die shoe, a holding member on the top die, a plurality of anvils on the holding member interfitting or mating with the anvils on the die shoe rigidly to hold the spoke ends in position adjacent the rim, a plunger on the top die adapted to act on the fixture, a plurality of punches movable to and from the rim and adapted to head the spoke ends at the rim, means to move the punches, the movement of said top die toward said die shoe causing the plunger to strike the fixture and the top die to come in contact with the pad to force the pad downward to cause the punch moving means to move the punches to head the spoke ends at the rim. 5
2. In a machine for riveting the short spokes of a wire wheel between the hub shell and rim, a die shoe including a reciprocable pad mounted therein, means on the pad to position the assembled hub shell, rim and spokes, a fixture secured in the hub shell and abutting the headed ends of the spokes rigidly to hold them in their openings in the shell, a plurality of anvils on the die shoe adjacent the rim to receive and positively position the spoke ends, a top die movable to and from the die shoe, a holding member on the top die, a resilient element between the holding element and the top die, a plurality of anvils on the holding member interfitting or mating with the anvils on the die shoe rigidly to hold the spoke ends in position adjacent the rim, a plunger on the top die adapted to act on the fixture, a plurality of punches movable to and from the rim and adapted to head the spoke ends at the rim, means to move the punches, the movement of said top die toward said die shoe causing the plunger to strike the fixture and the top die to come in contact with the pad to force the pad downward to cause the punch moving means to move the punches to head the spoke ends at the rim. 20
3. In a machine for riveting a plurality of spokes of a wire wheel between the hub shell and the rim, a die shoe having a pad resiliently and reciprocably mounted therein, a plurality of anvils shaped to receive the spokes and circularly arranged on the pad, a plurality of punch slides circularly arranged in the pad for sliding movement to and from the anvils, punches in said slides, said die shoe having arms pivoted to a stationary part thereof and to the punch slides and adapted to move the slides toward and away from the rim when the pad is reciprocated, a top die reciprocable relative to the die shoe and adapted to cause the reciprocation of the pad, a plurality of anvils on said top die mating with and cooperating with the anvils on the die shoe, said anvils on the die shoe and on the top shoe adapted firmly to grip and hold the spoke ends in the rim, and means to move the top die relative to the die shoe to cause the reciprocation of the pad and the movement of the punches to rivet the spoke ends. 25
4. In a machine for riveting a plurality of spokes of a wire wheel between the hub shell and the rim, a die shoe having a pad resiliently and reciprocably mounted therein, a plurality of anvils shaped to receive the spokes and circularly arranged on the pad, a plurality of punch slides circularly arranged in the pad for sliding movement to and from the anvils, punches in said slides, said die shoe having arms pivoted to a sta- 30

- tionary part thereof and to the punch slides and adapted to move the slides toward and away from the rim when the pad is reciprocated, a top die reciprocable relative to the die shoe and adapted 5 to cause the reciprocation of the pad, a plurality of anvils on said top die mating with and cooperating with the anvils on the die shoe, said anvils on the die shoe and on the top shoe adapted firmly to grip and hold the spoke ends at the 10 rim, means to move the top die relative to the die shoe to cause the reciprocation of the pad and the movement of the punches to rivet the spoke ends, and means on the top die to grip and raise the wheel from the die shoe when the top die is moved 15 away from the die shoe.
5. In a machine for riveting a plurality of spokes of a wire wheel between the hub shell and rim, a die shoe having a pad resiliently and reciprocably mounted therein, a plurality of anvils shaped to receive the spokes and circularly arranged on the pad, a plurality of punch slides circularly arranged in the pad for sliding movement to and from the anvils, punches in said slides, said die shoe having arms pivoted to a 20 stationary part thereof and to the punch slides and adapted to move the slides toward and away from the rim when the pad is reciprocated, a top die reciprocable relative to the die shoe and adapted to cause the reciprocation of the pad, a 25 plurality of anvils on said top die mating with and cooperating with the anvils on the die shoe, said anvils on the die shoe and on the top shoe adapted firmly to grip and hold the spoke ends at the rim, a plurality of punches slidably mounted in the pad, and means on the die shoe interconnected 30 with the punches to cause the punches to head the spoke ends when the pad is reciprocated.
6. In a machine for riveting a plurality of spokes of a wire wheel between the hub shell and rim, a die shoe having a pad resiliently and reciprocably mounted therein, a plurality of anvils shaped to receive the spokes and circularly arranged on the pad, a plurality of punch slides circularly arranged in the pad for sliding movement to and from the anvils, punches in said slides, said die shoe having arms pivoted to a 35 stationary part thereof and to the punch slides and adapted to move the slides toward and away from the rim when the pad is reciprocated, a top die reciprocable relative to the die shoe to cause the reciprocation of the pad, and the movement of the punches to rivet the spoke ends.
- 40 7. In a machine for riveting a plurality of spokes of a wire wheel between the hub shell and rim, a die shoe having a pad resiliently and reciprocably mounted therein, a plurality of anvils shaped to receive the spokes and circularly arranged on the pad, a plurality of punch slides circularly arranged in the pad for sliding movement to and from the anvils, punches in said slides, said die shoe having arms pivoted to a 45 stationary part thereof and to the punch slides and adapted to move the slides toward and away from the rim when the pad is reciprocated, a top die reciprocable relative to the die shoe and adapted to cause the reciprocation of the pad, a plurality of anvils on said top die mating with and 50 cooperating with the anvils on the die shoe, said anvils on the die shoe and on the top shoe adapted firmly to grip and hold the spoke ends at the rim, a plurality of punches slidably mounted in the pad, resilient means between the gripping members and the top die, said resilient means being under compression when the spokes are riveted, and means on the die shoe interconnected 55 with the punches to cause the punches to head the spoke ends when the pad is reciprocated.
8. In a machine for riveting a plurality of spokes of a wire wheel between the hub shell and rim, a die shoe having a pad resiliently and reciprocably mounted therein, a plurality of anvils shaped to receive the spokes and circularly arranged on the pad, a plurality of punch slides circularly arranged in the pad for sliding movement to and from the anvils, punches in said slides, said die shoe having arms pivoted to a 60 stationary part thereof and to the punch slides and adapted to move the slides toward and away from the rim when the pad is reciprocated, a top die reciprocable relative to the die shoe to cause the reciprocation of the pad, and the movement of the punches to rivet the spoke ends.
- 65 9. In a machine for riveting a plurality of spokes of a wire wheel between the hub shell and rim, a die shoe having a pad resiliently and reciprocably mounted therein, a plurality of anvils shaped to receive the spokes and circularly arranged on the pad, a plurality of punch slides circularly arranged in the pad for sliding movement to and from the anvils, punches in said slides, said die shoe having arms pivoted to a 70 stationary part thereof and to the punch slides and adapted to move the slides toward and away from the rim when the pad is reciprocated, a top die reciprocable relative to the die shoe to cause the reciprocation of the pad, and the movement of the punches to rivet the spoke ends.
- 75 10. In a machine for riveting a plurality of spokes of a wire wheel between the hub shell and rim, a die shoe having a pad resiliently and reciprocably mounted therein, a plurality of anvils shaped to receive the spokes and circularly arranged on the pad, a plurality of punch slides circularly arranged in the pad for sliding movement to and from the anvils, punches in said slides, said die shoe having arms pivoted to a 80 stationary part thereof and to the punch slides and adapted to move the slides toward and away from the rim when the pad is reciprocated, a top die reciprocable relative to the die shoe to cause the reciprocation of the pad, and the movement of the punches to rivet the spoke ends.
11. In a machine for simultaneously riveting a plurality of short spokes of a wire wheel between the hub shell and rim, a lower die shoe adapted to receive the assembled hub shell, short spokes and rim, a fixture secured within the hub shell to back the heads of the spokes and hold the heads rigidly in the spoke openings, a plurality of circularly arranged and reciprocably mounted punches carried on the lower die shoe, means carried on the lower die shoe to move the punches, a top die movable to and from the lower die shoe, cooperating anvils on the top die and lower die shoe to grip and rigidly hold the spoke ends at the rim and means actuated by the movement of the top die toward said lower die shoe to 85

operate the punch moving means to move the punches to head the spokes at the rim.

12. In a machine for simultaneously riveting a plurality of short spokes of a wire wheel between the hub shell and rim, a lower die shoe adapted to receive the assembled hub shell, short spokes and rim, a plurality of circularly arranged punch slides slidably mounted on the lower die shoe, punches carried in each slide, means to move the slides, a top die movable toward and away from said lower die shoe, a holding element mounted on the top die, resilient means between the holding element and the top die, cooperating

mating anvils circularly arranged in the holding element and in the lower die shoe and having co-operating grooves to receive the spokes adjacent the rim and to rigidly hold them, the movement of the top die toward the lower die shoe causing the mating anvils to grip the spokes and to place the resilient means under compression and means actuated by the downward movement to operate the means to actuate the punch slides inwardly to cause the punches to head the spokes in the rim. 10

HERMAN TORMYN.
FRANK F. WIETHOFF.
